UNITED STATES PATENT OFFICE.

CHARLES F. MUELLER, OF ELIZABETH, NEW JERSEY.

TUNING-HAMMER.

SPECIFICATION forming part of Letters Patent No. 634,016, dated October 3, 1899.

Application filed October 27, 1898. Serial No. 694,665. (No model.)

To all whom it may concern:

Be it known that I, CHARLES F. MUELLER, a citizen of the United States, residing at Elizabeth, in the county of Union and State 5 of New Jersey, have invented certain new and useful Improvements in Tuning-Hammers; and I do hereby declare the following to be a full, clear, and exact description of the invention, such as will enable others skilled in 10 the art to which it appertains to make and use the same, reference being had to the accompanying drawings, and to letters of reference marked thereon, which form a part of this specification.

15 The objects of this invention are to secure a more firm connection of the hammer-head and its handle to more certainly prevent breakage and the consequent loss of the handle, to secure a more easy and quick adjustment of parts during the piano-tuning operations, and to secure other advantages and results, some of which may be referred to hereinafter in connection with the description of the working parts.

20 25 The invention consists in the improved piano-tuner's hammer and in the arrangements and combinations of parts of the same, all substantially as will be hereinafter set forth and finally embraced in the clauses of 30 the claim.

Referring to the accompanying drawings, in which like letters of reference indicate corresponding parts in each of the several views, Figure 1 is a front elevation of the 35 improved hammer. Fig. 2 is a central longitudinal section of the same. Fig. 3 is a transverse section taken at line *x*, Fig. 1. Fig. 4 is a detail showing the threaded end of a certain shank-clamping clutch. Fig. 5 is an end 40 view of the same. Fig. 6 is a detail view of the rear portion of the shank, showing a certain key or spline thereon; and Fig. 7 is a sectional view of the same, taken on line *y*. Fig. 8 is a sectional view taken at line *z*, Fig. 45 2, and showing more particularly certain peculiarities in the end cap or screw for steady- 2, and showing more particularly certain pec- ing the shank-clutch.

In said drawings, *a* indicates a handle of the shape commonly employed in piano-tuning 50 hammers, preferably made of rosewood or other strong wood, the said hammer-handle

being about ten inches, more or less, in length, so as to enable the piano-tuner to grasp the same with two hands in certain piano-tuning operations. The said handle is longitudinally and axially bored out, and in the boring is fitted a longitudinal core-tube *b*, the said tube being inserted with as great nicety of adjustment as possible to prevent any movement of said tube *b* within said handle. The 55 forward end of said core-tube is threaded and is screwed within the correspondingly-threaded interior of the handle, so as to prevent any longitudinal movement of said tube within said handle. The threaded forward extremity of said tube *b* projects half an inch, more or less, forward from the end of the handle and is at its projecting end longitudinally slotted, as indicated at *cc* in Figs. 4 and 5, the plurality of slots at the end forming fingers *c'*, 60 65 which serve to clutch or clamp the shank *d* of the hammer. At the projecting end the said tube is beveled or provided with inclines *e*, adapted to be engaged by the coöperating inclines or bearings of the clamp-nut *f*. The fingers *c'* have more or less resiliency, so that they may spring away from the shank *d* when released from the clamp-nut. Upon the said threaded extension or projecting end of the tubular core is placed said clamp-nut *f*. 70 75 This is provided interiorly with the inclines referred to, which engage the inclined ends of the tube-fingers. It is also provided with threads which engage the threaded tube and is perforated to permit the passage there- 80 85 through of the shank. Thus when said nut is placed upon said shank and upon said threaded tube and screwed upon the latter the inclines are brought into operative relation to force the fingers of the slotted tube 90 firmly against the shank to hold the same rigidly in position, and the rigid holding is accomplished with great facility and ease without requiring the use of screw-drivers or like articles, such as have been heretofore required. 95

At the rear end the core is provided with a longitudinal slot or groove *g* to receive a key or spline *h*, the said spline being fastened to or formed on the shank *d* near its rear end and 100 adapted to slide in said tube, fitting the groove so that there is no looseness permit-

ting of lateral movement. The said shank is thus adapted to slide longitudinally within the said tube a limited distance or until the end of the spline engages the forward end wall 5 of the tube-slot. This sliding operation is accomplished only when the clamp-nut *f* is released from clutching engagement with the clutch end of the tube.

It sometimes becomes necessary, more especially when the wooden handle shrinks, to give greater firmness to the core-tube within the handle, and to this end I employ at the rear of the handle a steadyng-nut *i*, which is threaded to enter the threaded rear end of 15 the core-tube *b* and fit nicely a recess in the handle. The said screw *i* is provided with an annular groove *i'* on the inner side, around the threaded shank *j* thereof, into which groove the core-tube *b* fits closely, and thus 20 the said tube is held with greater firmness, conduced to greater steadiness and firmness of the hammer, especially when the latter, with its shank *d*, is withdrawn.

The shank *d* projects beyond the projecting end of the core-tube a distance sufficient 25 to permit of the arrangement of the clamp-screw *f* thereon and to receive the hammer-head *k*. At the extremity forward of said clamp-screw the said shank is provided with 30 a thread *d'*, upon which the hammer-head *k* is screwed. Said hammer-head is of ordinary construction, having the usual forwardly-inclined arms *k' k'*, which are provided with wrenching-sockets (shown in outline in Fig. 1) 35 in the usual manner. The screw-thread at the projecting end of the shank is of standard size, so as to receive the ordinary hammer-head commonly provided, and thus there may be a quick interchange of heads, or the 40 purchaser of the handle may employ hammer-heads already in his possession.

It will be evident that the spline *h*, formed 45 as described, by having a long bearing in the slotted tube *b* gives to the shank and hammer-head a greater wrenching strength than the ordinary set-screws heretofore provided, and thus there is no danger when turning the music-pins of the hammer-head slipping in the handle and producing an improper tuning 50 in the piano, which requires great nicety of touch and firmness of grasp of the operating-

tools, as will be well understood by those skilled in the art.

Having thus described the invention, what I claim as new is—

1. In a piano-tuning hammer, the combination with a core-tube, clamp-nut, and longitudinally-adjustable shank, of means preventing rotary movement of said shank in any of its longitudinal positions, substantially as set forth. 60

2. In a piano-tuner's hammer, the combination of a core-tube having a longitudinal slot and grasping-fingers, a clamp-nut, and a shank sliding longitudinally in said core-tube 65 and having a spline engaging said slot therein and preventing rotary movement of the shank, substantially as set forth.

3. In a piano-tuning hammer, the combination with the handle, of a core-tube fixed 70 in said handle and having a longitudinal slot, a shank sliding longitudinally in said core-tube and having a spline fitting said slot and preventing rotary movement, and means for clamping said shank against longitudinal 75 movement, substantially as set forth.

4. In a piano-tuning hammer, the combination of a core-tube having a longitudinal slot opening at the rear end and said rear end being threaded, a shank longitudinally adjustable in said core-tube and having a spline 80 engaging said slot, and a cap screwed onto said rear end of the core-tube to prevent spreading, substantially as set forth.

5. The improved tuner's hammer having a 85 handle, a slotted core-tube interiorly threaded at its back end and exteriorly slotted at its forward end and screwed into said shank-handle, the threaded forward end projecting from said handle and where projecting having grasping-fingers for clamping the shank, a nut, a shank fitting into said tube and having a spline, and a steadyng-nut at the back end of the handle engaging said tube, substantially as set forth. 90

In testimony that I claim the foregoing I have hereunto set my hand this 11th day of October, 1898.

CHARLES F. MUELLER.
